UNITED STATES PATENT OFFICE.

WALTER E. OLIVER, OF WOODCLIFF, NEW JERSEY, ASSIGNOR TO AUTOGRAPHIC REGISTER COMPANY, OF HOBOKEN, NEW JERSEY, A CORPORATION OF NEW JERSEY.

STARTING MECHANISM FOR MANIFOLDING DEVICES.

Application filed September 5, 1925. Serial No. 54,617.

The present invention relates to restarting mechanism for autographic registers or the like, particularly of the type wherein the restarting wheel is connected with the 5 shaft on which it is mounted by friction clutch, so that the restarting wheel may remain idle during part of its rotation. A device of this type is shown in my co-pending application, Ser. No. 506,291, filed 10 October 8, 1921. For the purposes of illustration, I show the present invention applied to the mechanism set forth in said earlier application to which reference is made for a more complete showing of various 15 parts of the machine.

When the restarting wheel is held by friction engagement with the driving shaft on which it is mounted, it sometimes happens that the friction is too slight to cause this 20 wheel to operate. The present invention relates particularly to a method of overcoming these difficulties.

In the accompanying drawings which 25 show an illustrative example of my present invention as applied to the structure shown in my said earlier application, Ser. No. 506,291, Fig. 1 shows the various parts in the position which they occupy when the restarting wheel is held stationary; Fig. 2 shows 30 the parts at the time that restarting begins, and Fig. 3 is a perspective showing the details of the novel structure covered by the present application.

For the purposes of simplicity, parts that 35 are common to the present application and to the said earlier application, are given the same reference letters as are applied in the earlier application. Attention is particularly called to Fig. 6 of the earlier applica- 40 tion.

Numeral 39 designates a feed roller under which pass the paper strips 9. Beneath the roller 39 is a shaft 44, loosely mounted on which is an auxiliary roller 50. At the sides 45 of the roller 50, attached to shaft 44, are two collars 47. Roller 50 is held in position with relation to one collar 47 by a spacing sleeve 51. Between the roller 50 and the other collar 47 is a compressed coil spring 50 52, the tendency of which is to cause the

auxiliary roller 50 to revolve with the shaft 44 due to friction. The auxiliary roller 50, in the form here shown, is made up of a plurality of disk-like laminations locked together by pins, and its general conformation is cylindrical. One surface of the roller is however flattened at 50^a; and diametrically opposite this flat surface, a recess 50^b is cut in one end of the roller to coact with a restraining pawl 62. Under normal conditions the feed roller 39 will engage with roller 50 except when the flattened surface 50^a is presented to the feed roller.

Roller 50 is normally held against rotation with shaft 44, due to the fact that pawl 62 is in engagement with recess 50^b. However, when pawl 62 is moved out of recess 50^b, roller 50 will turn with shaft 44 and will cause the paper strips 9 to advance. Up to this point the mechanism described is the same as that shown in my earlier application.

In order to insure the operation of roller 50, shaft 44 carries a toothed portion 100 which is embraced between the sides of the 75 roller 50. A small toothed roller 102 is loosely mounted on a pin 104 in such a way that this roller can engage with the tooth 100 on shaft 44, but can move out of such engagement. The roller 102 is positioned 80 adjacent one edge of the flat portion 50^a of roller 50.

When the roller 50 is held from rotation by pawl 62, roller 102 can remain idle. However, after the release of pawl 62, as 85 roller 50 advances towards the position shown in Fig. 2, roller 102 will engage with the paper sheets 9 and will be held in engagement with teeth 100. The teeth that are uppermost on roller 102, due to the fact 90 that they have engaged with the paper strips, will tend to remain stationary, but the operation of shaft 44 will rotate roller 102, causing it to move under roller 39. This movement of roller 102, acting through 95 pin 104, will assist to draw circular portion of roller 50 under roller 39. As soon as roller 102 passes out from engagement with the paper sheets, roller 50 will serve to cause the paper sheets to advance.

What I claim is:

1. In combination, a roller, a shaft adjacent the roller, a member having a portion of its circumference adapted to cooperate with the roller mounted on said shaft, friction mechanism connecting said shaft and said member, and means carried by said member adapted to supplement said friction

mechanism to cause said member to move into cooperation with the roller. 10

2. A device as characterized in claim 1, in which said means comprises a supplemental toothed roller carried by said member, and adapted to be rotated by engagement with said shaft.

WALTER E. OLIVER.
